UNITED STATES PATENT OFFICE.

JAKOB PFEIFFER-BRAUN, OF LAUPEN, NEAR BERN, SWITZERLAND.

LACING FASTENING.

Application filed August 25, 1927, Serial No. 215,497, and in Germany June 30, 1927.

This invention relates to a fastener for boot and like laces and consists in the provision on a stud of corniform, pivoted lever arms the points of which are adapted to meet and 5 form a support about which the lace end can be looped, the arms being spring-controlled and adapted to be closed and retained in closed position by means of a shackle.

Fig. 1 of the accompanying drawings represents a front view of the device in closed position,

Fig. 2, a view of the same showing the open position,

Fig. 3, a side view of a device having two 15 pairs of fastening arms and a pivoted retaining shackle,

Fig. 4, a top view, partly in section, of Fig. 3,

Fig. 5, a front view of the same, and 20 Fig. 6, a view illustrating the principle on which the fastener is constructed.

Referring to Fig. 6 which shows a lace *k* looped about a rod *m*, it will be evident that a pull on either end of the lace *k* will secure the latter all the tighter to the rod instead of detaching it from the same. However, even if the lace is very firmly tightened to the rod in this manner, the detachment of the lace can easily be effected by pulling the rod 30 out of the loop.

The lacing fastening according to the present invention operates on this principle.

The rod *m* is replaced by two corniform lever arms, such as *c* in Fig. 1, which are 35 pivoted to a stud *a* or the like, the latter, which need not be larger than one of the usual lacing hooks applied to boots and shoes, being secured as the final lace holder to the laced article. The arms are spring-pressed 40 and tend to open out as shown in Fig. 2. For

fastening the lace, the end of the latter is looped as shown in Fig. 1, and the arms are closed so that the points meet inside the loop and form, like the rod *m*, a continuous support about which the loop can be tightened 45 under the tension of the lace. For closing the arms and retaining them in closed position, a shackle *g* may be used which is itself retained on the arms by snapping into notches *i* in the latter. One arm may have a 50 point *n* adapted to enter a corresponding recess *o* at the end of the other arm so as to prevent relative displacement of the closed arms.

To undo the fastening the shackle *g* is removed, whereupon the arms can be separated however tightly the loop should happen to be secured.

Two pairs of arms, *c* and *d*, may be mounted on the same stud, as shown in Figs. 3 and 60 4 for connection to different ends of the lace. In this case two shafts *b* are employed each of which carries two arms controlled by a single spring *f*. The closing and retaining shackle *g'* is pivoted to the stud *a* so that it 65 can be turned into and out of operative position.

I claim:

A lacing fastening comprising a support, two parallel distanced shafts mounted in said support, corniform lever arms secured to the ends of said shafts so that the arms can be closed in pairs point to point, a spring tending to open the arms, and a shackle adapted to embrace a pair of arms and to snap into notches in the same for retaining the arms in closed position, the shackle being pivoted to the support so as to allow of being turned into and out of operative position.

JAKOB PFEIFFER-BRAUN.
